POWER TROMMEL

Florian F. Dauenhauer, 2860 Lomitas Ave.,
Santa Rosa, Calif.
Filed Nov. 14, 1960, Ser. No. 68,739
6 Claims. (Cl. 209—308)

The invention, in general, relates to machines for separating hops from foreign material comprising leaves, fragments of leaves, hop clusters, vine stems, both large and small, as well as other debris. More particularly, the invention relates to a power driven pocket trommel operating as a first cleaner following the stripping of the hops from the hop vines in a hop-picking machine, and wherein appreciable quantities of separated foreign material are removed continuously to prevent any clogging or stopping of the machine.

The present application primarily relates to an improvement of the pocket trommel heretofore invented by applicant and described and claimed in United States Letters Patent No. 2,376,128, granted to applicant on May 15, 1945. In operation, the pocket trommel of the aforementioned Letters Patent effected the removal of substantial quantities of individual hops but was required to be stopped from time to time during the hop-picking and hop-cleaning operations by reason of the fact that accumulations of debris and foreign material interfered with the continued agitation of the trommel endless screen and, further, effective separation of individual hops and the foreign material could not be accomplished with the facility afforded by the present improvement which is directed to the combination of added components in advance of the agitating screen as well as added components below the agitating screen for increasing the efficiency of the trommel operation as well as for decreasing to a minimum the number of stoppages of the equipment during any hop-picking and hop-cleaning operation.

A primary object of the present invention is to provide an improved power trommel containing the feature of diffusing and spreading the mixtures of picked hops and foreign material so as to deposit individual hops and heavy foreign material in different areas of the trommel.

Another important object of the present invention is to provide a power trommel of the indicated nature which is additionally characterized by the provision of means for constantly removing large branches, hop clusters and the like which are carried over the agitating pulley of the trommel and for delivering this material to one of the units of the picking machine for increased diffusion or dispersion so as to enhance the recovery and the rate of recovery of clean hops.

A still further object of the present invention is to provide an improved power trommel of the aforementioned character which includes the features above mentioned without appreciably increasing the cost of manufacture of the unit or the cost of maintenance thereof.

Other objects of the invention, together with some of the advantageous features thereof, will appear from the following description of a preferred embodiment of my present improvement which is illustrated in the accompanying drawings. It is to be understood, however, that I am not to be limited to the precise embodiments shown, nor to the precise arrangement of the component parts thereof, as my invention, as defined in the appended claims, can be embodied in a plurality and variety of forms.

Referring to the drawings:

FIG. 1 is a side elevational view of a preferred embodiment of the present improvement.

FIG. 2 is a sectional elevational view thereof, taken on the line 2—2 of FIG. 1.

FIG. 3 is a fragmentary perspective view of the agi-

2

tating idler pulley and embodied in the preferred embodiment of the present improvement.

FIG. 4 is a composite view showing sectionally the means for effecting the agitation of the screen belt to taunt as well as to permit slackening of the same whereby the mixtures of hops and foreign material are appreciably tumbled about.

FIG. 5 is a reduced top plan view of the preferred embodiment of the invention in association with components of a hop-picking machine.

FIG. 6 is a schematic showing of the driving mechanism for the improved power trommel illustrated in FIGS. 1 and 2.

In its preferred form, the power trommel of my present improvement preferably comprises, in combination with a conveyor for delivering mixtures of picked hops and foreign material, an endless mesh belt for receiving the delivered mixtures and for separating the hops from the foreign matter, means for agitating said belt to tumble the mixtures about and to enhance the action of separating the hops from the foreign material, together with a separating and diffusing member movably supported in overlying relationship to said mesh belt between said conveyor and said belt for spreading and diffusing the delivered mixtures to different areas of said mesh belt, and driven means in underlying relationship to said endless mesh belt for effecting the continuous removal of separated foreign material and for preventing the clogging of the trommel.

As particularly illustrated in FIGS. 1 and 2 of the annexed drawings, the power trommel of the present improvement, which is designated generally by the reference numeral 11 in the accompanying drawings, receives mixtures of picked hops and foreign material from a hop-picking machine, designated generally by the reference numeral 12, through the medium of an elevator conveyor 13. In general, the trommel 11 comprises an endless mesh belt 14 which conveniently can be a chain belt fashioned of chain links to afford a plurality of square openings 15 therein of sufficient size, say approximately 1 3/4" mesh, to pass the average size of hop. The mesh can be diamond-shaped, rather than square, as desired, and the entire belt may be fabricated of wire, if desired. The endless mesh belt 14 is trained over a driven pulley 16 as well as an agitating idler pulley 17 and a smaller idler pulley 18, as shown; the pulleys being journaled in brackets secured to structural members of a preferably steel framework which is designated generally by the reference numeral 19 and which includes an upright 21 on which the driven pulley 16 is rotatably mounted, an upright 22 on which the smaller idler pulley 18 is rotatably supported, and an upwardly projecting inclined supporting member 23 upon which the agitating idler pulley 17 is rotatably mounted. The raised structural supporting member 23 elevates the agitating idler pulley 17 with respect to the driven pulley 16 so that the endless mesh belt 14 operates through a pocket section P at the approximate longitudinal center of the trommel from which it rises sharply up and over the agitating idler pulley 17, as shown.

In accordance with the present improvement, means are provided on the trommel 11 for separating and diffusing the mixtures of hops and foreign material which are delivered to the trommel by the elevator conveyor 13. These means preferably comprise a plurality of rods or tines 31 which are arranged in spaced relationship and pivoted as a unit, on a common pivot axle 32 spanning two spaced uprights 33 and 34 which are fixedly secured to a horizontally extending cross-beam 36 forming one component structural member of the steel framework 19 of the trommel. By this construction, the tines 31 are in the general form of a fork 37 and these tines are pivotally

mounted in overlying relationship to the endless mesh belt 14 of the trommel with the fork 37 located between the upper end or discharge outlet of the elevator conveyor 13 and the mesh belt 14 of the trommel so that the delivered mixtures of picked hops and foreign material encounter the fork 37 before being deposited upon the belt 14. As is well known, the stripping of hops from hop vines results in heterogeneous mixtures of individual hops, hop clusters comprising a plurality of hops depending from vine sections, leaves and fragments of leaves, as well as quantities of long and short vine stems. These mixtures constitute the matter carried by the elevator conveyor 13 for delivery to hop separator devices of which the power trommel 11 constitutes one and which aptly may be termed a first cleaner. The pivot axle 32 of the fork 37 is journaled in the uprights 33 and 34 and is arranged to hold the group of tines 31 in the inclined position indicated by the full line showings of FIG. 2; this inclined position of the fork 37 being maintained by a counterweight 38 secured to an extension 39 affixed to the common axle 32 and normally abutting on the top of the fork frame.

The fork 37 actually is a self-cleaning separator fork since the fork 37 will swing to the dotted line position illustrated in FIG. 1 when there is a sufficient load of hop clusters and leaves and stems and other foreign material adhering to or hanging from the fork as to overcome the weight of the counterweight 38. In normal operations, hops which are discharged from the top of the elevator conveyor 13 and which are separated from the foreign matter as to be loose therefrom will pass through the spaces of the fork 37 while the foreign material, comprising the hop clusters, leaves, fragments of leaves and the like, will strike the individual tines 31 of the fork 37 and slide down the same to strike the lower portion 41 of a deflector 42 which is affixed to the framework of the fork and which overlies the endless mesh belt 14 adjacent to the driven pulley 16 thereof so as to deposit the foreign material in an area designated by the reference character G, while the separated hops are diffused by the fork 37 to be distributed on an area of the endless belt 14 indicated by the reference character F, see FIG. 2 of the annexed drawings. Thus, the fork 37 functions to separate to some extent loose hops that are carried up to the trommel 11 on the elevator conveyor 13 and to separate out also the larger foreign material including large vine stems, branches and large clusters; the large material so separated by the fork 37 being deposited on the mesh belt 14 in an area so as not to interfere with the screening of the loose hops in the area F thereof.

In accordance with the present invention, the agitating idler pulley 17 is specially constructed so as to cause alternate tightening or tautening of the endless mesh belt 14 and loosening of the same to a slack state during its rotation about the three pulleys 16, 17, and 18 over which the belt is trained; the tautening and slackening action being recurrent and effecting a repetitive raising and lowering of the pocket section P of the trommel to appreciably tumble about the mixtures of hops and foreign material on the mesh belt 14 and to aid in the screening or separating of the individual hops from the mixtures of hops and foreign material as well as the passage of such separated hops through the mesh 15 of the belt. To this end, the agitating idler open-drum pulley 17 is formed with a pair of opposed heads 51 and arranged in spaced relationship and maintained in such positions by a plurality of cross-bars 52, 53, 54 and 55 which conveniently are removably secured by means of bolts to flanges formed by recessing the heads 51 of the pulley; alternate cross-bars 52 and 54 being of greater thickness, say 2 x 4" beams, than the alternate cross-bars 53 and 55 which can be 2 x 2" beams, and the cross-bars being preferably arranged at 90° intervals about the heads 51, as shown, such differences in thicknesses of the alternate cross-bars appreciably enhancing or increasing the tumbling action of the mesh belt about the pocket section P. In FIG. 4 of the annexed

drawings, I have illustrated the tautening of the mesh belt, as at 60, and the loosening or slackening of the belt, as at 60', as it alternately passes over the 2 x 4" cross-bars and the 2 x 2" cross-bars of the agitating idler drum pulley 17 in the rotation of the screen about the three pulleys 16, 17 and 18. It is to be noted that all vine branches, stems, leaves and clusters which are too large to pass through the mesh 15 of the trommel screen belt 14 are carried up and over the agitating idler pulley 17 to strike an inclined deflector 56, conveniently supported on the framework members 22' and 23; the deflector 56 serving to deliver this carried over foreign material to an area of the trommel floor 57, indicated by the reference character I, from which area the foreign material is removed by means of another important feature of my present improvement which aptly can be termed a drag conveyor, and which is designated generally by the reference numeral 58 in the annexed drawings. It is also to be noted that the individual hops which pass through the mesh 15 on the upwardly extending stretch or reach of the endless mesh belt 14 will strike against another inclined deflector 56' which serves to direct these hops onto a shaker conveyor hereinafter more particularly described, the deflector 56' conveniently being supported on structural members 22 and 36 of the framework 19.

The above referred to additional important feature of my improved power trommel comprises a pair of driven chains 59 and 61, arranged in parallel spaced relationship and maintained in such spaced relationship by a plurality of cross-slats 62 secured to the chains 59 and 61 at spaced intervals throughout their endless lengths; such cross-slats riding upon a sub-floor 57' which prevents the drag conveyor 58 from becoming slack. In accordance with the present improvement, the drag conveyor 58 is caused to move in the direction of the arrows 63, see FIG. 1 at the lower left, which is in the same direction of movement as the mesh belt 14 of the trommel, as indicated by the arrow 64. The two parallel chains 59 and 61 of the drag conveyor 58 are individually trained over aligned pairs of spaced sprockets 67 and 68 which are driven as hereinafter described. It is to be especially noted that the endless belt 14 is so driven as to travel at a faster rate than the drag conveyor 58 so that the endless belt 14 actually bumps over the slats 62 of the drag conveyor along the lower reach of the mesh belt 14, as particularly shown in FIG. 1, and it is also to be noted that the drag conveyor 58 is maintained in such position that it is in brushing engagement with the lower run or reach of the endless mesh belt 14 with the slats 62 riding on the floor 57 and thereby picking up and carrying all foreign material that passes up and over the idler pulley 17 of the trommel, and guided downwardly by the inclined deflector 56, for delivery to one section, designated by the reference numeral 71, of an upright picking machine 12. The end of the drag conveyor 58 adjacent to the one section of the picking machine 12 extends through an opening 72 in a wall 73 which partially encloses the upright picking machine 12 so that foreign material carried along by the drag or return of the endless mesh belt is brought within an area or path taken by the picking fingers 74 of the hop-picking machine 12; such picking fingers effecting the spreading and diffusion of the foreign material over a larger area for deposition on to a removal conveyor. It is to be noted that the picking fingers of the unit of the picking machine shown in the accompanying drawings move in the direction of the arrow 75 and up and over the upper pulley 76 of the picking machine so that some of the foreign material is carried upwardly to pass over the upper pulley and such hop clusters, leaves, stems and trash are uniformly distributed onto the removal conveyor, designated generally by the traveling grizzly mesh belt 77, which is movably mounted below the picking machine 12 and which delivers to an arm picker, not shown. By this action, the screening of loose hops from the clusters and the leaves which are brought within the unit of the hop-picking machine by the trommel re-

turn mechanism including the drag conveyor 58 is greatly enhanced and this increases the rate of recovery of clean hops that may have become embedded in the leaves, the stems and the clusters. As stated, the grizzly mesh conveyor 77 delivers the screened hop clusters, leaves and stems and whatever hops might remain therein to an individual picking machine known as an arm picker, not shown, where additional hops are stripped from the clusters and separated therefrom.

My improved power trommel also includes a shaker conveyor 81 which is movably supported within the trommel just below the upper arm of the endless mesh belt 14, as shown, and such shaker conveyor 81 preferably comprises an imperforate plate 82 so supported as to be disposed at an inclination to the horizontal and preferably supported by means of links, as hereinafter described, as to give an upward movement on the forward stroke of the plate 82 and a downward movement on the return stroke. The shaker conveyor is intermittently driven to and fro, and also rises and falls, as hereinafter described, by means of a shaker eccentric axle 84 on one end of which a V-pulley 86 is securely fastened; the shaker eccentric axle carrying a pair of spaced eccentric connecting rods 87 and 88 connected to the shaker plate 82 for moving the same to and fro. The shaker conveyor is conveniently movably supported for rise and fall by means of two pairs of spaced shaker arms 91 and 92 secured at their one ends to the uprights 22 by means of brackets 96 and 97 and at their other ends to the bottom of the shaker conveyor. The action of the shaker conveyor is intermittent, as stated, and the conveyor serves to deliver the material separated from the mixtures of hops and foreign material through the mesh 15 of the mesh belt 14 to the hop separating flights which are disclosed and claimed in my copending application entitled "Hop Separating Flights," Serial No. 68,749, filed November 14, 1960. Driving means for the eccentric axle 84 of the shaker conveyor 81 are described hereinafter in connection with other driving means for the trommel components.

While any suitable driving means can be employed for actuating the various shafts and axles of the trommel, I preferably employ an electric motor 101, see FIG. 6 of the annexed drawings, which is so mounted as to support a pulley 102 on the outer end of the motor shaft 103; the driving means including a counter-shaft 104 which is placed in driving connection with the motor 101 by a belt and pulley drive 106, 107, respectively. The counter-shaft 104 carries additional V-pulleys 108 and 109, and the pulley 108 is connected by means of a V-belt 111 to the V-pulley 86 of the shaker eccentric axle 84 whereas the pulley 109 is connected for the purposes of driving a shaft 110, through the medium of a twisted V-belt 112 and a pulley 113. The shaft 110 carries a sprocket 114 to effect the driving of a shaft 115, on which the driven pulley 16 of the trommel 11 is mounted, through the medium of a twisted endless chain 116 which is trained around the sprocket 114 as well as a corresponding sprocket on shaft 115. The driven shaft 115 serves to drive the drag conveyor 58 in the same direction of rotation as the direction of rotation of the trommel screen 14; the driving connections including a V-pulley 117 on shaft 115, the drag conveyor driven shaft 118, on which the pairs of sprockets 67 carrying the drag conveyor endless chains 59 and 61 are mounted, and a twisted V-belt 119 trained over the V-pulley 117 of shaft 115 and a corresponding V-pulley on shaft 118.

The improved power trommel herein illustrated and described affords enhanced separation of hops from leaves, stems, hop clusters and other foreign material with an increased rate of recovery of cleaned hops; the initial separating action occurring in the first cleaner by the action of the fork 37 which effects continuous deposition of individual separated hops on one area of the moving mesh belt 14 and continuous deposition of separated larger for-

5 eign matter to another area of the belt 14, thus greatly enhancing the effectiveness of the belt 14 and separating additional individual hops from the foreign material through the openings 15 of the mesh belt for deposit onto the shaker conveyor 81 which receives also the deposits of leaf fragments, some leaves, as well as some large and small stems that pass through the openings of the belt 14.

10 The increased raising and lowering of the pocket section P of endless belt 14 of the trommel, by virtue of the special construction of the agitating idler pulley 17, increases the tumbling of the mixtures and a greater separation of individual hops along the upper reach of the belt on its upward movement toward the pulley 17, with screened individual hops and other material being guided onto the shaker conveyor 81 by the guide baffle 56, and with the larger un-screened foreign material including larger stems, hop clusters and leaves being carried up and over the pulley 17 and guided down to the floor 57 of the trommel by the guide baffle 56. The trommel return, i.e., the lower reach of the belt 14 constantly bumps over the slats 62 of the drag conveyor 58 to additionally tumble and agitate the mixtures and at this section of the endless belt, which is continuous in its action, the drag conveyor 58 is constantly in brushing engagement with the belt 14 so that the foreign material deposited on the floor 57 continuously, including hop clusters still bearing individual hops as well as many hops embedded in the mixtures of large leaves and stems and clusters, will be moved in the direction of the arrow 63 into a section 71 of the hop-picking machine 12 where the upwardly moving finger bars are encountered and the fingers 74 engage and scatter the successive moving mixtures of hops and foreign material to uniformly spread the scattered mixtures onto a moving grizzly or mesh screen 77 movably mounted underneath the picking machine 12 and serving to carry the larger foreign material, including the hop clusters and the like, to an arm picker, not shown, for effectively stripping additional individual hops from the clusters. Some of the foreign material moving off of the drag conveyor 58 within the hop-picking machine 12 will fall by gravity onto an inclined guide or barrier 78 which is supported on the inside of an enclosure wall 73 and which terminates in close proximity to the grizzly 77, so as to carry the falling portions of the mixtures of foreign material from the drag conveyor 58 down to the grizzly 77.

40 It is to be understood that the appended claims are to be accorded a range of equivalents commensurate in scope with the advances made over the prior art.

45 50 I claim:

55 1. In a power trommel, a movable endless screen to which mixtures of hops and foreign material including hop vine leaves, fragments of leaves, hop clusters, vine stems and vine branches are delivered from a source of the mixtures, means supporting said endless screen to maintain a pocket section in the upper run thereof, means for repetitively raising and lowering said pocket section to repetitively and appreciably tumble about the mixtures of hops and foreign material delivered to said screen to 60 enhance the screening of hops from the mixture through said endless screen, a floor below said endless screen, means for effecting the deposition of un-screened foreign material onto said floor, a drag conveyor movably mounted between said endless screen and said floor in brushing engagement with the lower run of said endless screen and with said floor; said drag conveyor being adapted upon being moved with the movement of said endless screen to pick up and move away un-screened foreign material deposited on said floor thereby preventing fouling and stoppage of movement of said endless screen, and means for moving both said endless screen and said drag conveyor.

65 70 75 2. A power trommel comprising, in combination with conveying means having a discharge outlet for delivering to a predetermined location successive mixtures of hops

and foreign material including hop vine leaves, fragments of leaves, hop clusters and vine stems and branches, a stationary frame, a movable endless screen supported in underlying relationship to the discharge outlet of said conveying means for receiving said successive mixtures, a self-cleaning fork-like separator member pivotally supported on said stationary frame at said predetermined location in overlying relationship to said screen between the discharge outlet of said conveying means and said screen for diffusing said successive mixtures of hops and foreign material and for effecting the separation of individual hops and deposition thereof in one area of said screen and the deposition of larger foreign material on a different area of said screen; said self-cleaning fork-like separator member being moved on its pivot when overloaded with said mixtures of hops and foreign material to a vertical position thereby to rid itself of all such mixtures and being returned to an inclined position when rid of said mixtures of foreign material, a counter-weight connected to said separator member normally to hold the same in an inclined position, a plurality of pulleys journaled in said stationary frame supporting said endless screen to maintain a pocket section in the upper run thereof, means on one of said pulleys for repetitively raising and lowering said pocket section to repetitively and appreciably tumble about the hops and foreign material disposed on said screen, means for moving said endless screen to carry un-screened foreign material up and over the top of one of said pulleys for deposition below said screen, a floor on which un-screened foreign material is deposited, and a drag conveyor movably mounted below said endless screen and in brushing engagement with said floor and with the lower run of said screen to pick up and carry away foreign material disposed below said endless screen thereby to prevent fouling of and stoppage of movement of said endless screen.

3. A power trommel as defined in claim 2 and wherein said drag conveyor comprises a pair of endless chains arranged and maintained in parallel spaced relationship, and a plurality of cross-slats spanning said pair of endless chains at spaced intervals for brushing against said floor and the lower return run of said endless screen and for carrying away in conjunction with said endless screen and said floor the foreign material deposited below said endless screen.

4. A power trommel as defined in claim 3, and means for moving said pair of endless chains in the same direction of movement as the movement of said endless screen.

5. A power trommel and picking machine combination comprising, in combination with conveying means for delivering from the picking machine successive mixtures of hops and foreign material to a predetermined location, a stationary frame, an endless screen movably

mounted on said stationary frame in underlying relation to said predetermined location, a self-cleaning fork-like separator member pivotally mounted on said stationary frame at said predetermined location in overlying relation to said endless screen, a counter-weight connected to said fork-like separator member to maintain the same normally at an inclination to the vertical; overloading of said separator member with mixtures of hops and foreign material sufficient to overcome said counter-weight effecting a pivotal movement of said fork-like separator member to the vertical thereby effecting a self-cleaning thereof, means for maintaining a pocket in the upper run of said endless screen, means on said frame for effecting repetitive raising and lowering of said pocket of said screen for effecting the tumbling about of the successive delivered mixtures of hops and foreign material thereby to screen out individual hops from said mixtures, a floor underlying said screen, means for depositing un-screened foreign material on said floor, a drag conveyor movably mounted on said frame means, for moving both said endless screen and said drag conveyor, means on said drag conveyor for engaging said floor as well as the lower run of said endless screen for moving un-screened foreign material off of said floor to prevent fouling of and stoppage of said endless screen, and a partition between said endless screen of the trommel and said picking machine, said partition having an opening therethrough beyond which said drag conveyor projects and through which un-screened foreign material moved off said floor is passed onto said picking machine.

6. A trommel and picking machine combination as defined in claim 5, wherein said drag conveyor consists of a pair of chains arranged in parallel spaced relationship, and said means on said drag conveyor consists of a plurality of cross-slats connected to and spanning said pair of chains in spaced relation to one another.
